UNITED STATES PATENT OFFICE.

THOMAS W. R. McCABE, OF WATERBURY, CONNECTICUT, ASSIGNOR TO CHARLES H. HASBROUCK, OF BINGHAMTON, NEW YORK.

CHECK-PRINTING MACHINE.

1,353,926.

Specification of Letters Patent. Patented Sept. 28, 1920.
Application filed May 2, 1917. Serial No. 165,902.

To all whom it may concern:

Be it known that I, THOMAS W. R. McCABE, a citizen of the United States, residing at Waterbury, in the county of New Haven, State of Connecticut, have invented certain new and useful Improvements in Check-Printing Machines; and I do hereby declare the following to be a full, clear, and exact description of the invention, such as will enable others skilled in the art to which it pertains to make and use the same:

This invention relates to machines for imprinting characters upon checks, drafts, notes and other papers of similar character, the machine, more particularly, being of that character which are typified by the term "check writing machines."

It is in general the object of the invention to increase the efficiency of machines of this character, and to simplify and otherwise improve their structures with a view to the provision of a compact and durable mechanism which may be built at a comparatively low cost.

An important and more specific object resides in the provision of a check writing machine which upon the insertion of a check therein may be operated with one hand to print various successive symbols on the check, whereby the other hand of the operator is free to perform any desired operation.

Likewise, it is an object to provide a check writing machine in which the coaction of the printing wheel and the platen tend to feed the check or other strip through the machine so that a separate feeding means is unnecessary.

More particularly, it is the object of this invention to provide a check writing machine in which a printing drum or wheel is mounted for rotary movement and oscillatory action, the rotary movement being for the purpose of turning the various printing characters into printing position and the oscillating motion being communicated to the wheel for the purpose of carrying the wheel across the platen.

With the above objects in view, and such

others as may hereinafter appear as relating to the details of construction, my invention will now be fully set forth and described, reference being had to the accompanying drawings.

In the drawings:

Figure 1 is a front elevation of the machine,

Fig. 2 is a vertical sectional view taken transversely through the central portion of the machine,

Fig. 3 is a horizontal sectional view through the machine, with the parts in the position they assume just at the completion of the printing operation,

Fig. 4 is a vertical transverse section,

Fig. 5 is a section on line 5-5 of Fig. 3,

Fig. 6 is a horizontal section above the platen,

Fig. 7 is a longitudinal sectional view of a modified form of the mechanism, and

Fig. 8 is a transverse section thereof.

Referring more particularly to the drawings, 1 indicates a base upon which is mounted a casing 2, the latter being preferably a casting within which, upon its end walls, are formed the guide flanges 3. The latter are arranged in vertical pairs for a purpose which will hereinafter appear. Also, the casing 2, on its front face is formed with a vertical protuberance 4 having a slot 5 which forms a guide way through which the control member of the printing devices projects, as later described.

At the upper forward portion of the casing 2, the protuberance 4 terminates in an inclined table 6, into which the slot 5 is continued and upon which an indicating disk 7 is mounted. The disk 7 has impressed or otherwise provided thereon, in circular arrangement, a series of indicia 8, which forms the guide for the user of the machine from which he may set the printing wheel.

Supported for vertical sliding movement in the guide ways formed by the flanges 3 are the bearing blocks 9, which receive the trunnions 10 of a frame or yoke 11 which is thus pivotally mounted on a horizontal axis, and within which is mounted the printing wheel or drum 12. The bearing

65

100

blocks 9 are provided through their upper faces with the vertical bores 13 within which are seated the coil springs 14 whose upper or free ends bear against abutments 15 formed integrally with the casing, the action of the springs being thus to push the blocks 9 downwardly. The effect of the springs 14 is to push the bearing blocks 9 into contact with a pair of cam heads 16 which are pivotally mounted below the guide ways 3 upon the end walls of the casing. The cam heads 16 are provided with the arms or extensions 17 and 18 which extend respectively, below the front and rear sides of the yoke 11 in such operative relation that under certain circumstances which will be later defined, said front and rear sides will rock the arms 17 and 18 to cause the cam head 16 to raise or lower the bearings 9.

As above stated the printing wheel or drum 12 is mounted in the yoke 11, the shaft 19 supporting the drum extending forwardly through the bearing 20 which forms a part of the front side of the yoke, and continuing therefrom through the slot 5, the extended end thereof being provided with a knob or hand-grip 21 and also carrying a pointer 22 which is adapted to coöperate with the indicia 8 in setting the printing wheel for an operation. The normal position of the yoke 11 and the shaft 19 is inclined, as indicated in Fig. 2, the parts being normally drawn to and held in this position by means of a pair of springs 23 which are tensioned between the rear side of yoke 11 and the casing 2.

The wheel 12 is preferably a unitary casting whose periphery is sufficiently broad to accommodate a printing surface having the longest word or phrase which the machine is adapted to print or impress at a single operation. Furthermore, the periphery of the drum or wheel is transversely rounded, so that the drum is virtually a section of a sphere whose tangent is the platen surface, or rather, is that plane in which the printing is done.

Formed on the periphery of the drum or wheel 12, in parallel relation, is the series of printing characters 24 which in the present instance comprises written numerals, freely secured on the wheel, but which may be, without departing from the invention, removably attached in a suitable manner (not shown) whereby to permit the use of various words, phrases and characters which are required under different conditions in the writing of bank paper. Between each two printing characters 24 is formed a transverse groove 25 which, when the wheel is rocked into printing position, is adapted to receive the blade of a downwardly projecting locking lug 26 which is formed upon the casing 2. By means of this locking lug 26 the wheel is prevented from rotation out of

its accurate printing position during the printing operation.

Mounted upon a transverse axis in the base of the machine is a platen roller 27, the latter being located in recess 28 so that its periphery is operative just above the surface of the base 1 and may be contacted by the peripheral surface of the drum, or rather, by the printing surfaces carried by the drum. As the drum is swung into printing position, the paper to be printed is initially caught by the rear edge of the drum and the roller, so that as the drum is swung downwardly and rearwardly the paper is fed over the roller by the coaction of the latter with the printing surface simultaneously with the printing operation.

In order to strip the paper from the printing surface after printing operation or after each printing step and to hold the paper for the next printing step, a pair of strippers 29 is provided, said strippers consisting of spring plates which are secured to the front of the casing and have their stripping surfaces projecting rearwardly below the drum in such spaced relation as not to interfere with the coaction of the drum and platen but to prevent the paper being carried with the printing surface when the drum is lifted at the end of the printing stroke.

The drum or wheel 12 is inked by means of a pair of rollers 30 which are rotatable upon yokes or frames 31 pivotally suspended from the front and rear sides of the yoke 11, so that the rollers may normally rest against the periphery of the drum. A coil spring 32 stretched between the arms 31 maintains the rollers 30 in proper inking contact with the drum.

In the operation of the machine, the paper is introduced at the front of the casing through the slot 33 which is cut into the front wall across the entire width of the latter coincident with the upper surface of the base 1, and is ejected through a corresponding slot 33' beyond the rear wall of the machine. When the printing wheel is in the position indicated in Fig. 2, the front end of the paper will be caught between the rear edge of the drum 12 and the platen 27 at the first movement of the drum toward the rear, or, if it is necessary to position the paper this may be done prior to any initial swinging movement of the drum. It being assumed that the drum has been set to the desired printing position by rotation of the head 21 until the pointer 22 coincides with the proper character on the disk 7, the shaft 19 is then depressed in the slot 5. This action swings the yoke 11 and the drum 2 so that the paper which is caught between the periphery of the drum and the platen 27 is fed rearwardly and the characters upon the surface of the drum are embossed

or printed on to the paper. As the drum and yoke are rocked toward the rear, the descending front side of the yoke comes into contact with the arms 17 of the cams 16. 5 The construction of the cam head 16 is such that it will rock with the yoke without acting upon the lower ends of bearing blocks 9 until just at the close of the stroke or movement. At this time, however, the cams 10 16 ride under the lowest points of the blocks 9 and lift the latter, and therewith the yoke 11 and the printing wheel and this operation obviously lifts the printing wheel away from the platen 27 and releases the 15 paper, the strippers 29 pulling the paper away from the drum or wheel in the event that the latter should adhere to the embossing characters. As soon as the handle 21 is released, the springs 23 return the yoke 20 and drum to their original positions, the rear side of the yoke striking the arms 18 and thereby releasing the cams 16 from engagement below the ends of the blocks 9, so that the printing wheel may drop again into 25 position to contact the platen the next time the handle 21 is depressed.

In the modified form of the invention shown in Figs. 7 and 8, the printing wheel, yoke, and cam mechanism are somewhat 30 differently associated. The yoke 35 consists of forward and rear depending arms which extend from a transverse tubular bearing 36. The latter is supported on a shaft 37 which has its journal ends supported in 35 bearing blocks 38, the latter being, in turn, carried upon stems 39 which are vertically movable in guide blocks 40 which project inwardly from the walls of the casing. Springs 41, mounted on the projecting lower 40 ends of the stems 39, and bearing between the blocks 40 and pins 42 on the ends of the stems normally hold the bearing blocks 38 down against the guide blocks 40.

Mounted on reduced seats 43 cut into the 45 inner faces of the bearing blocks 38 are the collars 44, which, as best shown in Fig. 7, are provided with the enlargements or cams 45 which may bear upon and wipe over the upper faces of the blocks 40. Each of the 50 collars 44 is provided with a lug 46 which cooperates with a pair of spaced lugs 47 formed on the bearing 36, the lug 46 lying between the lugs 47 and the latter being so spaced that, at the end of the forward movement of the bearing 36, the rear lugs 47 strike the lug 46 and carry the cams 45 onto the blocks 40, thereby raising the printing wheel from the platen. Likewise, when the wheel returns to initial position, the foremost lugs 47 strike the lugs 46 at the end 55 of the stroke and remove the cams 45 from the blocks 40. The space between the forward and rear lugs provide for the return 60 of the wheel, in spaced relation of the

platen by retaining the cams 45 on the 65 blocks 40 during the major portion of return movement. By the above construction, the same results may be secured as defined for the preferred form.

From the foregoing, it will be apparent 70 that I have provided an improved and simplified form of check writing or printing device which is capable of as wide a range of usefulness in printing bank paper as other machines of more complicated design. 75 The printing action is accomplished through a combination of two movements, a swinging movement and a prior rotative setting movement, and by the operations based upon these two movements, the machine is capable 80 of rapid and accurate work.

What I claim as my invention is:—

1. A machine of the character described comprising a platen wheel, a printing wheel adapted to be moved in a curved path over 85 the platen wheel, means for retaining the printing wheel in engagement with the platen wheel during a printing operation, means for disengaging the printing wheel from the platen wheel immediately subsequent to the printing operation, and means for retaining the printing wheel out of engagement with the platen wheel during its 90 return movement over the platen wheel to a normal position. 95

2. A check writing machine comprising in combination, a casing, a yoke mounted to oscillate in the casing, vertically movable bearings supporting the yoke, a printing wheel rotatable in the yoke, means for setting the wheel, means for swinging the yoke and wheel, a platen to coöperate with the printing wheel, and means to lift the bearings at the end of a printing stroke to carry 100 the wheel away from the platen. 105

3. A check writing machine comprising in combination, a casing, a yoke mounted to oscillate in the casing, vertically movable bearings supporting the yoke, a printing element carried in the yoke, means for swinging the yoke and rotating the wheel, a platen to coöperate with said element, and cams actuated by the yoke to lift the element away from the platen at the end of a 110 printing stroke. 115

4. A check writing machine comprising in combination, a casing, a yoke mounted to oscillate in the casing, vertically movable bearings supporting the yoke, a printing wheel rotatable in the yoke, means for setting the wheel, means for swinging the yoke and wheel, a platen to coöperate with the printing wheel, means to lift the bearings at the end of a printing stroke to carry the wheel away from the platen, and means for locking the wheel against rotation during 120 the printing stroke. 125

5. A check writing machine comprising

in combination, a casing, a yoke mounted to oscillate in the casing, vertically movable bearings supporting the yoke, a printing wheel rotatable in the yoke, means for setting the wheel, means for swinging the yoke and wheel, a platen to coöperate with the printing wheel, cams actuated by the yoke to lift the wheel away from the platen at the end of a printing stroke, and means

to lock the wheel against rotation during the printing stroke.

In testimony whereof I affix my signature in the presence of two witnesses.

THOMAS W. R. McCABE.
